UNITED STATES PATENT OFFICE.

ALCÉE LANDRY, OF MARK, LOUISIANA.

GRAPPLE.

No. 856,708.

Specification of Letters Patent.

Patented June 11, 1907.

Application filed September 14, 1906. Serial No. 334,612.

To all whom it may concern:

Be it known that I, ALCÉE LANDRY, a citizen of the United States, residing at Mark, in the parish of West Baton Rouge and State of Louisiana, have invented certain new and useful Improvements in Grapples; and I do hereby declare the following to be a full, clear, and exact description of the invention, such as will enable others skilled in the art to 5 which it appertains to make and use the same.

My invention relates to improvements in grapples, and while it may be generally employed for loading and unloading cane, it is 15 particularly designed for use in the fields for gathering the sugar cane and loading same into cane carts.

One of the primary objects of the invention is to provide a device without flexible 20 connections in its main construction, where- by a strong and rigid grapple is produced.

Another feature of the invention is in the particular construction of the grapple, whereby it is completely closed around the 25 heap of cane upon operating the elevating means and when tripped will drop with the jaws open to their greatest extent in a position substantially vertical to the ground and will remain in such position when the grapple is 30 lowered to grab another heap of cane, whereby the greatest possible area is covered by the jaws.

Another feature of the invention is the particular flexible connection between the 35 elevating cable and the grapple jaws, whereby when the grapple has been tripped and the load of cane has opened the jaws to a certain extent, the weight of the device will be taken on the suspending flexible means and 40 the position of the pivotal connection between the jaws having been changed, the jaws will be opened to their fullest extent by gravity, the particular connection of the suspending flexible means with the grapple jaws 45 furnishing greater leverage to insure the complete opening of the jaws.

Another feature of the invention resides in the particular form of tripping mechanism for the grapple.

50 Other objects and advantages will appear from the following description, and while I do not restrict myself to the specific details illustrated and described, still for the purpose of disclosure and that the invention may be 55 more clearly understood, reference is had to the accompanying drawings, illustrating a

practical embodiment of same, in which like characters designate the same parts in the several views, and in which:—

Figure 1 is a view in side elevation, showing a cane loader provided with my improved grapple, in a position to be tripped over a cane cart connected to the rear of the cane loader, said cane cart being illustrated in dotted lines. Fig. 2 is a perspective view of my improved grapple shown in its closed suspended position. Fig. 3 is a view in side elevation of the grapple, shown in its extreme open position for grabbing a heap of cane, the flexible connections between the elevating means and the grapple jaws being shown partly broken away, and the elevating means and the tripping device being omitted, and Fig. 4 is a side elevation of the tripping device, the position of the tripping arm, 75 when the device is tripped, being also shown in dotted lines.

In Fig. 1 the cane cart illustrated is similar in construction to the cart shown and described in my application for Letters Patent 80 filed April 24, 1906, Serial No. 313,448, and for the purposes of the present application requires no further description than a brief reference to the parts.

1 designates the body or platform of the 85 wagon or cart, provided with a rotatably mounted mast 2, operating arm 3, pivoted boom 4, equalizer 5, winding drum 6, and band brake 7.

8 designates the mule cable fastened at one 90 end around said drum, and 9 is the elevating cable connected at one end to said drum and reeving over suitable pulleys and suspended from the outer end of said boom and connected to the tripping device hereinafter referred to.

10 is an adjusting cable connected to the equalizer 5 through a suitable block and tackle connection secured to the upper end of the mast 2, and 11 is a cable reeving over 100 suitably disposed pulleys carried by said boom and mast for adjusting the elevated position of said boom.

12 designates the jaws of the grapple which 105 may be of any suitable contour and having any suitable number of teeth. In the drawings at the upper end of the jaws, there are shown spaced extension arms 13 which may be an integral part of the bar forming the top of the jaw and being bent extensions of 110 the end jaw teeth. These spaced extension arms interlap each other and are pivotally

secured together as at 14, and at their upper free ends as at 15 are pivotally connected with links 16 connected together as at 17 by a suitable pivot means which may be in the form of a ring, as shown, the links 16 and the spaced extension arms 13 forming a lazy-tongs arrangement. The grapple jaws are also provided with the leverage arms 18 extending substantially at right angles to the position of the bars 13, and these leverage arms may be braced to the jaws by means of the brace rods 19.

The tripping device consists of the spaced member 20 provided with a suspending ring 21 and having a lateral extension 22, and a curved pin 23 on the opposite side to said extension.

24 is a latch pivotally connected between the spaced walls of said member 20, as at 25, engaged at one end by the tripping cable 26 and adapted to engage at its notched end with the upper end of the curved tripping arm 27 pivotally connected as at 28 at the bottom of said member 20.

29 designates a coil spring encircling the pin 23 and interposed between the latch 24 and the member 20 for holding said latch in its operative position.

30 designates flexible connections between the tripping device or elevating cable and the grapple jaws, forking off at their lower ends into three branches 31, one of said branches of each set being secured to the outer end of said leverage arm 18, and the other branches being secured to the grapple jaws proper.

It will be noted that the flexible means 30 do not act as tripping means and also that their upper ends are secured to the elevating means or tripping device so that the length of these flexible means remains constant, as contradistinguished from other devices wherein flexible means may be attached to the jaws of a grapple and employed to trip same, after the load has been elevated and the tripping cables secured, upon lowering the load.

It will also be observed that the leverage arms are so positioned with relation to the jaws that they never come within the limits of the lazy-tongs arrangement, that is to say they are disposed at a considerable distance to one side of the pivotal point 14, both in the closed and particularly the open position of the grapple. Also it will be observed that when the jaws are in their open position as well as when closed, the pivotal point 14, connecting the extensions on said jaws, lies in a plane above the teeth of the jaws, and hence when the grapple is being initially closed, the tendency of the hooks digging into the ground is not so great, owing to the leverage, as when the pivot connecting the arms is disposed in a plane below the top of the jaws.

65 From the foregoing it will be seen that

when the jaws are in the position shown in Fig. 3, the grapple is in its full extended position with the jaw teeth disposed substantially vertical and ready to be lowered to grab a heap of cane, the area of cane to be covered being the greatest possible within the limits of the device. In this position the elevating cable 9 is lowered and the tripping arm 27 passed through the ring 17 and locked, and upon motion being imparted to the elevating means, the jaws will close around a heap of cane and when completely closed will elevate same when it is swung to the cart. Upon releasing the tripping device, the load of cane will open the jaws a certain distance, when the weight of the jaws will be taken up by the flexible means 30.

It will be observed now that ordinarily the flexible means for suspending the jaws when the load is tripped, would simply hold the jaws in an open position, sufficient to allow of the dumping of the cane, but by my present construction it will be seen that the pivotal point 14 having been moved by the initial opening of the jaws, the flexible connection between the tripping device and the jaws will lie out of the center of gravity and hence the jaws will be further extended by their own weight, great leverage being first given by the leverage arms 18, and subsequently the strain being taken on the jaws proper through the two side branches 31.

Having thus described the invention, what I claim is:

1. In a grapple, the combination with a pair of jaws provided with extension arms pivotally connected together intermediate of their ends, of a pair of links pivotally connected together at one of their ends and at their other ends pivotally connected to the respective ends of said extension arms, and forming a lazy-tongs arrangement, a tripping device adapted to suspend the pivoted ends of said links, means for tripping said device to allow said lazy-tongs to collapse and initially open said jaws by the weight of the load, a leverage arm extending laterally and outwardly from each of said jaws and disposed in a position to be always to one side of said pivoting links and lazy-tongs and located at a substantial distance from the pivotal point of said jaws when said jaws are in their closed position, and intermediate means connected at one end to said tripping device and at their other ends branched and connected independently to said leverage arms and said jaws proper, substantially as described.

2. In a grapple, the combination with a pair of pivoted jaws, of a tripping device for detachably suspending said jaws from an elevating cable, comprising a spaced base member provided with a tripping lever bent substantially at right angles to form a long and short arm, said short arm being pivotally se-

cured to said base member, a spring controlled latch pivotally mounted at the opposite end of said base member and notched to engage the free end of said long arm when disposed in a vertical position, means for operating said latch to trip said bent lever, and inextensible flexible connections interposed between said tripping device and said jaws, substantially as described.

10 3. In a grapple, the combination with a pair of jaws provided with extension arms pivotally connected intermediate of their ends, a pair of links pivotally connected together at one end and at their other end pivotally connected to the respective free ends of said extension arms forming a lazy-tongs arrangement; a tripping device adapted to suspend said lazy-tongs device comprising a spaced base member having a lateral extension thereon, and provided at its lower end with a pivoted curved arm adapted to seat,

in its locked position between said spaced extension, and provided at its upper end with a spring-operated pivoted latch having a notched end adapted to engage the free end of said curved tripping arm; means for tripping said latch; a leverage arm provided on each of said jaws and extending outwardly therefrom at a position on one side of said pivotal points and said lazy-tongs arrangement, and inextensible flexible means connected to said tripping device at one end and at their other ends branched and connected independently to said leverage arms and said jaws proper, substantially as described. 35

In testimony whereof, I affix my signature, in presence of two witnesses.

ALCÉE LANDRY.
